CHISEL FOR SLATE-SPLITTING MACHINES

Eugene T. Lake, Brodheadsville, Pa.

Application January 12, 1950, Serial No. 138,151

4 Claims. (Cl. 125—36)

1

This invention relates to a chisel for a slate-splitting machine.

For many centuries, slate, after being removed from the quarry, was split into thin sheets by hand. This hand work involved a great deal of skill, labor and waste of slate, as well as being time-consuming. Machines for splitting slate have heretofore been known, as for example, that shown in the U. S. patent to Vincent F. Lake, No. 1,590,385, dated June 29, 1926. In that machine, a chisel blade is reciprocated very rapidly by mechanical means against the slate along the natural lines of cleavage of the slate. These machines used chisels such as shown in Fig. 11 of the patent, or blades such as shown in the Vincent F. Lake patent, No. 1,229,622, dated June 12, 1917. These were broad blades composed of a plurality of flexible portions co-planar but spaced short distances from each other. It was found that individual portions or fingers of the blade spaced short distances apart were somewhat unsatisfactory in that slivers could get between them. The object of my invention is to provide an improved form of chisel for such machines, in which the chances of slate being caught between the individual fingers of the blade are reduced to a minimum, and the ability of the chisel to work the slivers out of itself is greatly improved. My invention is characterized by the fact that the edge of the chisel blade is sheared or split from a single piece of material without the removal of any metal, except as necessary to smooth off burrs or fins produced by the shearing. In this way the individual fingers are in full contact with each other at the cutting edge and for some distance back from it. Back of the cutting edge a longitudinal extension is made of each such shearing line in the form of a slot formed by cutting out metal. These slots are considerably longer than they are wide. It is found that by not removing any metal for some distance back from the cutting edge, the chances of slivers getting between the individual portions or fingers of the blade are minimized, and that if the slivers do get in they gradually work themselves back to the open slots. The slots being longer than they are thick, the slivers will drop out.

In the drawings,

Figure 1 is an edge view of a slate-splitting chisel made in accordance with my invention;

Figure 2 is a view of the chisel of Fig. 1 on its width;

Figure 3 is a cross-section of the lower edge of the chisel taken on the line 3—3 of Fig. 2, show-

2

ing the reduced edge which, riding in a groove, serves to guide the chisel blade in its reciprocation, while

Figure 4 is a diagram of the shape of the cutting edge of the chisel, taken on the same plane and scale as adjacent Figure 1, except that the thickness of the blade is multiplied in order that the angles of the wedge and flanks can be seen diagrammatically. My slate-splitting chisel is mounted and operated in a manner similar to the chisel shown in the Lake patent, No. 1,590,385, above-mentioned. The blade is shown placed with its width in a vertical dimension, but it should be understood that it can be used in any other desired dimension. In machines of this general type, the chisel is adapted to give many thousands of blows per minute to the slate. No single blow is as strong as the single blow of a hand splitter, the desired result being obtained because of the greater number of blows applied. With such a type of action, it is necessary that the edge of the chisel be broken at a number of points particularly when splitting thin slate. This enables the resulting independent portions of the chisel to follow any local variations in cleavage planes in the slate, which avoids breakage of the slate. As indicated above, experience with such machines shows that relatively long slivers of slate tend to become wedged between the blades, destroying their flexibility holding a finger out of line with its neighbors and making it necessary to shut down the machine for cleaning.

My chisel blade 1 is mounted on a socket bar 35 or shank 2, at the rear end of which is a roller 3 adapted to receive the impacts from the operating cam (not shown). The blade is mounted on the shank by means of rivets 4, there being a washer 5 at the rear end of the blade 1 to provide a shoulder for a spring (not shown). Intermediate the washer and the roller is a regulating notch 6 having impact edges 7 cooperating with a regulating slide (not shown) to adjust the blows as desired.

The blade 1 itself is a broad symmetrical tapered blade of resilient material and preferably is substantially the width of the slate to be split. It maintains this width from the edge to a point a little short of the length of the slots shown. It tapers down from this width at that point to the width of the shank which carries it. The taper is indicated by the reference character 14. The cutting edge of the blade is in the shape of a symmetrical wedge 9. This wedge is of a higher angle than the flank 10. This has been found a de-

sirable form of chisel for splitting slate (see Fig. 4). As explained in the Lake patent, No. 1,229,-622, above-mentioned, in order to enable the blade to follow any local variations in the planes of the slate, each finger 8 of the cutting edge of the blade must be free to move slightly out of line of the neighboring fingers. In accordance with the two Lake patents mentioned above, slots were sawn at spaced points along the cutting edge, straight back. Instead of removing metal from the cutting edge, I propose to shear or split the blade at spaced points along the cutting edge. These splits or shearing lines are indicated in the drawings by the reference character 11. As shown, these shearing lines extend past the wedge 9 well into the flanks 10 of the blade. By not removing any metal from the cutting edge but merely shearing the metal, the chance of splinters of slate getting in between the individual fingers 8 of the cutting edge is minimized. Experience shows that occasionally, even under these conditions, slivers will get in between the fingers of the blade. Such slivers, of course, are very thin and are many times as wide as they are thick. I have discovered that such slivers as get into the sheared lines of my new blade can be removed by providing an actual slot 12 back of each sheared line, in extension thereof. Of course, metal has to be removed to form the slot. These slots are long enough to enable the entire sliver to work out of the sheared line and free itself into the slot where the metal has been removed.

As shown in Fig. 2 of the drawings, the shank end of the blade has a tapered form narrowing the blade down to approximately the size of the socket. It is known that with such a taper the outside fingers 8 at the top and bottom are slightly more flexible than the neighboring fingers between them. This is desirable because the slate at the edges of the block is generally not as strong as at the center of the block. This weakness of the outside fingers, however, is uneven because the taper comes from only one side. To make this weakness of the outside fingers more even and prevent twisting with the resultant risk of damage to the slate, I have extended the slots into the tapered portion. It will be noticed that these slots 11 are at least as long as the sheared lines in a new blade. I find that cutting metal out for a width of $\frac{1}{8}$ of an inch is sufficient to enable any slivers that get caught in the sheared lines to work themselves free and drop out in the open slots. Since clogging by splinters can jam the machine or cause breakage of the blade, it is therefore necessary, in case of clogging, to stop the machine and clear it at once. It will be obvious that my provision of sheared lines rather than open slots is a great practical improvement and that backing up these sheared lines with open slots to enable the machine to clear itself automatically is a still further improvement. The use of a slot back of the sheared lines which is at least equal to the length of the wedge will enable practically all slivers to free themselves. I prefer the longer slots shown.

This invention of the sheared lines in the blade is peculiarly useful in splitting thin slate where the danger of a sliver breaking the slate is great. I find that when dealing with a relatively thick block of slate, not only does the chisel have to go in a lesser distance before the splitting occurs

but the slate will be strong enough to crush a sliver instead of being broken by the sliver. It is, therefore, possible, when splitting relatively thick slate, to use one of my new blades which has been worn down in splitting thin slate until the cutting edge has reached the open slots 12.

As in the case of the prior Lake patents, I prefer to guide the lower edge of the chisel blade in a groove to which the bottom edge 13 of reduced thickness (see Fig. 3) fits in but slides freely.

Where in the claims I speak of "split lines" in making the chisel, it should be understood that I refer to dividing lines, whether produced by shearing or otherwise splitting the metal.

What I claim is:

1. A chisel for a power-driven slate splitting machine comprising a blade of resilient material having a wedge for a cutting edge, the blade maintaining its maximum width for a substantial distance back of the cutting edge and then tapering toward the opposite end of the blade, said blade being divided along a plurality of spaced lengthwise lines throughout at least substantially its maximum width into a plurality of fingers by split edges in contact with each other at the cutting edge of the chisel and for some distance back of the wedge, in combination with narrow elongated slots forming linear extensions of the split edges, the length of each slot being at least of the order of the length of its split: for the purposes described.

2. A chisel for a slate-splitting machine according to claim 1 in which there is a shank on which the blade is mounted, the blade being tapered in width at the shank end, the slots in the blade extending as far as but not beyond the first part of the tapered portion of the blade, whereby any tendency of the outside fingers of the cutting edge to twist is minimized.

3. A chisel for a slate-splitting machine according to claim 1 in which each slot is cut of uniform width for a distance equal substantially to the length of the sheared line of which it is an extension.

4. A chisel for a power-driven slate splitting machine comprising a blade of resilient material having a wedge for a cutting edge, the blade maintaining its maximum width for a substantial distance back of the cutting edge and then tapering toward the opposite end of the blade, said blade being divided along a plurality of spaced lengthwise lines throughout at least substantially its maximum width into a plurality of fingers by split edges in contact with each other at the cutting edge of the chisel and for some distance back of the wedge, in combination with narrow elongated slots forming linear extensions of the split edges, the length of each slot being sufficient to enable the edges of the split to deflect out of the plane of the chisel till clear of each other without permanent deflection.
